UNITED STATES PATENT OFFICE.

CORNELIUS G. GERTZ, OF FAIRVIEW, OKLAHOMA.

PLOW-POINT.

No. 888,607.

Specification of Letters Patent.

Patented May 26, 1908.

Application filed March 24, 1908. Serial No. 422,966.

To all whom it may concern:

Be it known that I, CORNELIUS G. GERTZ, a citizen of the United States, residing at Fairview, in the county of Major, Oklahoma, have invented certain new and useful Improvements in Plow-Points; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in points for plows and the object in view is to produce a simple and efficient device of this nature which may be readily applied to a plow share which has become worn to such an extent as to render it practically useless.

The invention comprises various details of construction, combinations and arrangements of parts which will be hereinafter fully described and then specifically defined in the appended claims.

My invention is illustrated in the accompanying drawings, in which:

Figure 1 is a perspective view showing my improved plow point as attached to a plow share. Fig. 2 is an elevation of the land side of the plow with the point attached. Fig. 3 is a perspective view of the point before being welded to the plow share.

Reference now being had to the details of the drawings by letter, A designates a plow share with the point portion thereof worn away forming a depression, designated by letter B, from constant wear and which has a tendency to render the plow practically useless.

C designates a plow point, made of a blank of metal, as shown clearly in Fig. 3 of the drawings. Said blank, which is wedge shaped at one end and having diagonally disposed edges, has one end contracted or narrow and of substantially the same width one-half its length. One of the edges of said blank has an upset bulging portion D along the straight edge of the blank and said bulging portion is designed to engage the worn away part E upon the plow share.

In applying the device to the plow share, the blank of metal is heated and bent upon

itself at F forming the point of the plow and the bulging portion D fills up the worn away space at the tip of the plow share, as shown clearly in Fig. 2 of the drawings. The flaring or wedge shaped end of the blank is welded down flush with the turning surface of the plow share, while the narrow portion of the blank, which extends underneath the plow share, is flush with the bottom of the latter and the straight edge of the blank, when the latter is bent upon itself, is flush with the land side of the plow share. Said blank forming the point of the plow has a counter-sunken rivet or bolt passing through the same and the plow share which, together with the welding, will securely hold the device in place.

From the foregoing, it will be noted that, by the provision of a plow point made as shown and described, a worn plow may be made practically as good as new.

It is my purpose to make the blanks as shown in Fig. 3 of the drawings and in readiness for attachment to any ordinary plow share which becomes worn and, by the simplicity of the device, the same may be readily applied to various forms of plow shares.

What I claim to be new is:

1. A point for plows comprising a blank of metal having a wedge-shaped end with tapering edge, an upset bulge along one of the marginal edges of the blank and designed as the latter is bent about the plow share to fill up the worn away tip of the latter, as set forth.

2. A point for plows comprising a blank of metal which is wedge-shaped at one end and provided with a straight and an inclined edge, one end of the blank being contracted, said straight edge being upset to form a bulge designed, when the blank is welded about the tip of a plow share, to fill in the worn away portion on the upper edge of the plow share, the surface of the blank adjacent to the bulging portion designed to engage the upper and lower surface of the plow share, as set forth.

3. A point for plows comprising a blank of metal which is wedge-shaped at one end and provided with a straight and an inclined edge, one end of the blank being contracted, said straight edge being upset to form a bulge designed, when the blank is welded about the tip of a plow share, to fill in the worn away portion on the upper edge of the plow share,

the surface of the blank adjacent to the bulging portion designed to engage the upper and lower surface of the plow share, the straight edge of the blank, when the device is applied
5 to a plow, being flush with the land side, and the tapering edge flush with the tapering edge of the plow share, as set forth.

In testimony whereof I hereunto affix my signature in the presence of two witnesses.

CORNELIUS G. GERTZ.
